CLAIM

The ornamental design for an X-ray digital imaging device as shown and described.

DESCRIPTION

The file of this patent contains at least one drawing executed in color. Copies of this patent with color drawings will be provided by the Office upon request and payment of the necessary fee.

FIG. 1 is a top surface-side perspective view of an X-ray digital imaging device, showing the new design;

FIG. 2 is a front view thereof;

FIG. 3 is a rear view thereof;

FIG. 4 is a right side view thereof;

FIG. 5 is a left side view thereof;

FIG. 6 is a top view thereof;

FIG. 7 is a bottom view thereof;

FIG. 8 is an enlarged view of portion 8-8 in FIG. 4;

FIG. 9 is an enlarged view of portion 8-8 in a changed state;

FIG. 10 is an enlarged view of portion 8-8 in an alternate changed state;

FIG. 11 is an enlarged view of portion 8-8 in a turned-off state; and,

FIG. 12 is an enlarged view of portion 8-8 showing a usage state thereof.

The broken lines shown in the drawings illustrate portions of the X-ray digital imaging device and form no part of the claimed design. The dash-dot-dash broken lines define the bounds of the claimed design and form no part thereof.
